FORMULA IIIwherein n is at least 1 and $m+n$ is greater than 10.

FORMULA VI

wherein n is at least 1 and $m+n$ is greater than 10.

FORMULA V

wherein n is at least 1 and $m+n$ is greater than 10.

FORMULA VI

wherein n is at least 1 and $m+n$ is greater than 10.

FORMULA VII

wherein n is at least 1 and $m+n$ is greater than 10.

FORMULA VIII

wherein n is at least 1 and $m+n$ is greater than 10.

FORMULA IX

wherein n is at least 1 and $m+n$ is greater than 10.

4
FORMULA Xwherein n is at least 1 and $m+n$ is greater than 10.

FORMULA XI

wherein n is at least 1 and $m+n$ is greater than 10.

FORMULA XII

wherein n is at least 1 and $m+n$ is greater than 10.

FORMULA XIII

wherein n is at least 1 and $m+n$ is greater than 10.

FORMULA XIV

wherein n is at least 1 and $m+n$ is greater than 10.

FORMULA XV

wherein n is at least 1 and $m+n$ is greater than 10.

FORMULA XVI

wherein n is at least 1 and $m+n$ is greater than 10.

5
FORMULA XVIIwherein n is at least 1 and $m+n$ is greater than 10.

FORMULA XVIII

wherein n is at least 1 and $m+n$ is greater than 10.

FORMULA XIX

wherein n is at least 1 and $m+n$ is greater than 10.

FORMULA XX

wherein n is at least 1 and $m+n$ is greater than 10.

FORMULA XXI

wherein n is at least 1 and $m+n$ is greater than 10.

FORMULA XXII

wherein n is at least 1 and $m+n$ is greater than 10.

FORMULA XXIII

wherein n is at least 1 and $m+n$ is greater than 10.

6
FORMULA XXIVwherein n is at least 1 and $m+n$ is greater than 10.

10 For the preparation of photoconductive elements, it is advantageous for the compounds of the general formula to be soluble in organic solvents, such as tetrahydrofuran, or any other solvent in which compounds are at least partially soluble. Such solutions are applied to substrates suitable for electrophotography and the solvent is then removed. Mixtures of solvents can also be used. If the polymer is essentially insoluble, it can be melted and applied to the substrate while in a liquid state.

20 The substrate material, if one is desired, may be any which satisfy the requirements of electrophotography such as metal, glass, paper, or plastic. Unless it is to be used in a device employing dual corona discharge, such as U.S. 2,922,883, the substrate should preferably have a conductivity greater than 10^{-1} ohm $^{-1}$ cm. $^{-1}$.

25 Applications of the solutions of the polymers of the general formula to the substrate is in the usual manner, such as spraying, doctor blade, meniscus, etc., followed by drying.

30 The polymers of the present invention absorb below the visible region of the electromagnetic spectrum, i.e.—below 4000 Å. Accordingly, their spectral sensitivity to the visible region may be improved by the addition of dyestuff sensitizers. In addition, activators or electron acceptors which increase the photoconductivity of the polymers of the present invention may also be applied with the polymers in preparing the photoconductive element. When added in a layer with the polymer, the activator or electron acceptor may be in molar amounts up to and beyond equivalent molar amounts of each monomeric unit in the copolymer. The only limitation on the amount of the activator or electron acceptor in the polymer layer is the dark conductivity. That is, high concentration of some activators or electron acceptors increase the dark conductivity to an extent that the photoconductive element is not useful in electrophotography. Examples of dyestuff sensitizers and activators or electron acceptors useful with the polymers of the present invention are found in U.S. Patent 3,232,755.

35 50 One type of electrophotography process in which the polymers of the invention are useful is known as xerography. This process comprises the laying down of a uniform electrostatic charge on a photoconductive insulating layer comprising at least one of the polymers of the invention, exposing the electrostatic charge surface to a pattern of light to effect decay of the charge in the illuminated areas, and contacting the latent electrostatic image thus formed with colored electroscopic powder to render the image visible. Next, a copy sheet is brought into contact with the developed image and transferred thereto and fixed thereon. The residual powder remaining on the photoconductive insulating element is removed by cleaning and the element is then ready for the preparation of the next copy or the next cycle.

40 55 60 65 The general nature of the invention having been set forth, the following examples are now presented as to the specific preparation of polymers falling within the general formula and the specific preparation of these polymers into the photoconductive elements which are then used in electrophotographic processes. The specific details presented are for purposes of illustration.

65 70 Example I.—Five grame (0.035 mole) N-vinylindole and 4.1 g. (0.035 mole) indole were weighed into a heavy walled Pyrex¹ polymerization tube. The mixture was de-

75 1 Trademark of Corning Glass Works.

gassed for several hours under vacuum, then sealed at 10^{-5} mm. Hg. The tube was heated in an oil bath at 150° C. for 24 hours. The light yellow viscous product was dissolved in benzene and precipitated in a large volume of methyl alcohol. After drying for 14 hours at 60° C., 4.0 g. (45% conversion) of a white powdery solid was obtained. The intrinsic viscosity of the polymer (Formula I) determined in benzene was 0.20. The melting point range was indefinite for the polymer turned brown at 250° C. and became black at 300° C.

The elemental analysis for $(C_{18}H_{16}N_2)_x$ calculated on a basis of a 50/50 copolymer was as follows:

Calculated (percent): C, 83.04; H, 6.19; N, 10.76. Found (percent): C, 82.82, 83.01; H, 5.98, 6.10; N, 10.29, 10.34.

Example II.—Five grams of N-vinylindole (0.035 mole) and 4.58 g. (0.035 mole) freshly distilled N-methylindole were weighed into a heavy walled Pyrex polymerization tube. The tube contents were degassed and sealed as in Example I, then heated in an oil bath at 150° C. for 24 hours. The light yellow viscous product, obtained upon cooling, was dissolved in benzene and precipitated in 800 ml. methyl alcohol. The white precipitate was re-dissolved and re-precipitated, then dried at 60° C. for 16 hours giving 6.2 gm. (64.5% conversion) white powdery polymer (Formula II). The intrinsic viscosity in benzene was 0.24 and the melting point range was 220 to 230° C. Elemental analysis for $(C_{19}H_{18}N_2)_x$ indicated a 50/50 copolymer:

Calculated (percent): C, 83.17; H, 6.61; N, 10.21. Found (percent): C, 83.19, 83.06; H, 6.42, 6.58; N, 10.17, 10.31.

Example III.—N-vinylindole, 14.3 g. (0.01 mole) and 13.1 g. (0.1 mole) freshly distilled N-methylindole were added to 75 ml. dry benzene in a 250 ml. 3-necked polymerization flask equipped with stirrer, thermometer, condenser and nitrogen gas inlet tube. The mixture was heated to 50° C. in an oil bath, then 0.33 g. (0.002 mole) azobisisobutyronitrile catalyst was added. The temperature of the mixture was raised to 70° C. and the polymerization continued for 24 hours under a nitrogen blanket. The mixture was cooled, poured into 100 ml. methyl alcohol to give a heavy white precipitate. The precipitate was dissolved in benzene, filtered through a 5-micron millepore filter into 800 ml. methyl alcohol. The precipitate was dried under vacuum 24 hours to give a 4.7 g. (17.5% conversion) white powdery solid. The polymer (Formula II) had an intrinsic viscosity of 0.06 and a softening range of 198–216° C. Elemental analysis for $(C_{19}H_{18}N_2)_x$ indicated a 50/50 copolymer:

Calculated (percent): C, 83.17; H, 6.61; N, 10.21. Found (percent): C, 83.08, 83.17; H, 6.27, 6.29; N, 10.55, 10.67.

Example IV.—Five grams (0.035 mole) pure N-vinylindole and 4.05 g. (0.035 mole) freshly distilled indene was mixed then transferred to a heavy walled Pyrex tube. The monomer mixture was degassed and sealed as in previous examples, then heated at 150° C. for 96 hours and at 200° C. for an additional 20 hours. A clear viscous mass was obtained which was dissolved in hot tetrahydrofuran and precipitated as a white solid in 800 ml. methyl alcohol. Upon drying for 14 hours at 60° C. 3.9 g. (43% conversion) of a white powder polymer (Formula VI) was obtained which melted from 165 to 173° C. and had an intrinsic viscosity in tetrahydrofuran of 0.05. The elemental analysis for $(C_{19}H_{16}N)_x$ indicated 50/50 copolymer.

Calculated (percent): C, 88.34; H, 6.24; N, 5.42. Found (percent): C, 87.54, 87.72; H, 6.38, 6.50; N, 5.99, 6.05.

Example V.—Five grams (0.035 mole) pure N-vinylindole and 5.1 g. (0.035 mole) coumarin were mixed intimately, then transferred to a heavy walled Pyrex glass polymerization tube. The mixture was degassed, sealed, then heated at 200° C. for 48 hours. The dark viscous mass obtained was twice dissolved in hot tetrahydrofuran

and precipitated from cold methyl alcohol. A light tan solid polymer (Formula VIII) 4.5 g. (44.5% conversion) was obtained after drying 16 hours at 60° C.; M.P. >300° C. which had an intrinsic viscosity in tetrahydrofuran of 0.24. Elemental analysis for $(C_{19}H_{14}NO_2)_x$:

Calculated (percent): C, 78.87; H, 5.23. Found (percent): C, 80.98, 81.13; H, 5.78, 5.94.

Example VI.—N-vinylindole, 10.9 g. (0.077 mole) and maleic anhydride, 7.5 g. (0.076 mole) were added to 285 g. of methylene chloride in a 500 ml. 3-necked polymerization flask equipped with stirrer, thermometer, condenser, and nitrogen gas inlet tube. The mixture was heated to 40° C. in an oil bath. Then 0.09 g. (3.8×10^{-4} mole) of benzoyl peroxide catalyst was added. The polymerization was continued for 22 hours under a nitrogen blanket. The mixture was cooled, poured into 1000 ml. of hexane to give 11.9 g. (68% conversion) of a red colored solid precipitate. The polymer (Formula VII) had a softening range of 146–153° C. The elemental analysis for

calculated on the basis of a 85/15 copolymer was as follows:

Calculated (percent): C, 78.60; H, 5.70; N, 8.31. Found (percent): C, 78.46, 78.51; H, 5.83, 5.89; N, 7.90, 7.94.

Examples VII–XII.—Photoconductive elements were prepared from the polymer of Examples I, II, IV, V, and VI by forming five separate solutions of 2,4,7-trinitro-9-fluorenone and each of the polymers, except for the polymer of Example VI, in a ratio of .7 mole of 2,4,7-trinitro-9-fluorenone to 1 monomeric unit of the copolymer using tetrahydrofuran as the solvent. The ratio of 2,4,7-trinitro-9-fluorenone to the copolymer of Example VI was .62 to 1. The solutions were coated on five separate aluminum substrates with a doctor blade set on a 5 mil wet gap. After drying, the photoconductive layers had a thickness of 7–8 microns. The thus prepared photoconductive elements were tested for this photoconductive and electrophotographic properties on the electrometer described in U.S. Pat. S.N. 690,775, filed Dec. 15, 1967 and assigned to the same assignee. The results of tests are shown in the following table.

Polymer	Negative charge, volts	Maximum speed, $t_{1/2}^*$ seconds
N-vinylindole-indole	500	3.1
N-vinylindole-N-methylindole	700	3.5
N-vinylindole-indene	620	3.1
N-vinylindole-coumarin	350	3.8
N-vinylindole-maleic anhydride	140	12.0
N-vinylindole-N-vinyl-2-methylindole	520	3.6

* $t_{1/2}$ is the exposure time required to reach one-half of the original electrostatic surface potential applied to the photoconductive element.

While the invention has been shown and described with reference to preferred embodiments thereof, it will be appreciated by those skilled in the art that variations in form may be made therein without departing from the spirit and scope of the invention. For example, it will be understood that the compounds are not limited as photoconductors in the mode electrophotography known as xerography, but may be used in persistent electrophotographic methods such as that described in U.S. Pat. No. 2,845,348 or any other method where the photoconductor is exposed before charging. In addition, even though the greatest demand for the present invention is in conjunction with electrophotography, the compounds are also particularly well suited for other photoconductive applications.

What is claimed is:

1. An electrophotographic process comprising the steps of forming an electrostatic charge pattern on a photo-

conductive element comprising a photoconductive polymer having the following structural formula:

wherein R is selected from the group consisting of hydrogen and lower alkyl, wherein R' is a fused ring radical, and wherein n is at least 1 and m+n is greater than 10.

2. The process of claim 1 wherein the polymer has the following structural formula:

wherein R is selected from the group consisting of hydrogen and lower alkyl, wherein X is selected from the group consisting of O, S, CH_2 and NR^2 , wherein R^2 is selected from the group consisting of hydrogen and lower alkyl, and wherein n is at least 1 and m+n is greater than 10.

3. The process of claim 1 wherein the polymer has the following structural formula:

wherein R^3 is selected from the group consisting of hydrogen and lower alkyl, and wherein n is greater than 10.

4. The process of claim 2 wherein the polymer has the following structural formula:

wherein n is at least 1 and m+n is greater than 10.

5. The process of claim 2 wherein the polymer has the following structural formula:

wherein n is at least 1 and m+n is greater than 10.

6. The process of claim 1 wherein the polymer has the following structural formula:

10 wherein n is at least 1 and m+n is greater than 10.

7. The process of claim 1 wherein the polymer has the following structural formula:

20 wherein n is at least 1 and m+n is greater than 10.

8. The process of claim 1 wherein the polymer has the following structural formula:

25 wherein n is at least 1 and m+n is greater than 10.

9. The process of claim 1 wherein the polymer has the following structural formula:

30 wherein n is at least 1 and m+n is greater than 10.

10. The process of claim 1 wherein the polymer has the following structural formula:

35 wherein n is at least 1 and m+n is greater than 10.

40 wherein n is at least 1 and m+n is greater than 10.
